UNITED STATES PATENT OFFICE.

DANTE RASO, OF BROOKLYN, NEW YORK, ASSIGNOR OF ONE-THIRD TO ANGELO MELUCCI AND ONE-THIRD TO CONSTANTINO PELLEGRINO, BOTH OF BROOKLYN, NEW YORK.

AUTOMATIC GAS IGNITER.

REISSUED

Application filed August 6, 1928. Serial No. 297,608.

My invention relates to automatic gas igniters and more particularly to an igniter adapted to ignite said burner initially and to re-ignite said burner automatically should the flame be extinguished for any cause.

The flame of a gas burner, such as the burner of a gas range commonly used for domestic cooking, is frequently extinguished by water which boils over, by drafts, etc. 10 The attendant is often unaware that the flame has been put out, or he or she may be absent from the room or house at the time, so that the burner is not immediately re-ignited. In such event, the gas escapes into 15 the room and the atmosphere becomes contaminated with a poisonous and explosive gas whereby the lives of persons in the room or elsewhere in the house, and particularly of sleeping persons, are endangered.

20 It is an object of the present invention to provide an automatic igniter which will automatically re-ignite a burner should the flame of the latter be accidentally extinguished, the igniter serving also to ignite the 25 burner initially upon operation of the usual hand valve.

It is a further object of the present invention to provide an automatic igniter which can be readily attached to burners 30 now in use, which is simple and sturdy in construction, is inexpensive to manufacture, and is positive and reliable in operation.

Other objects will appear from the following description and the features of novelty will be pointed out in the appended 35 claims.

In the drawing which shows, by way of example, a preferred form of my invention without defining its limits,

40 Figure 1 is a side elevation of a burner with my automatic igniter in position thereon;

Figure 2 is a similar view, partly in section; and

45 Figure 3 is a plan view of the same. Referring to the drawing, 10 indicates a burner of any usual or known construction having a feed-pipe 11 connected thereto and controlled by any suitable valve (not 50 shown). The gas flowing through the pipe 11 escapes through and burns at the openings 12 in the burner in the well-known manner.

My novel automatic igniter is composed, of a member 13 in the form of an elbow 55 having a tubular vertical section 14 which passes through the wall of the pipe 11 and projects into the interior thereof. The section 14 terminates at its lower end along a plane which is inclined to the vertical and 60 is thereby provided with an enlarged inlet in the path of the gas flowing through the pipe 11. The horizontal section 14' of the member 13 is formed of a tubular portion whose lower half has been cut away along 65 a plane at an angle to the axis of such section thereby providing a curved hood or shield which is elevated relatively to the burner 10. The upper portion of the vertical section 14 is completely closed except for 70 an approximately horizontal opening 15. The member 13 may be connected to the pipe 11 in any desired way, as by drilling a hole in said pipe and tapping the same so as to cooperate with an external thread on the 75 section 14, or by welding the parts together, etc.

A pilot tube 16, which is connected to the gas supply line in advance of the valve controlling the pipe 11, is operatively associated with the member 13 and terminates at a point adjacent and slightly below the opening 15. Where a number of burners are employed, each of them will have a separate pilot tube and all of the latter may be controlled by a single needle or other valve to regulate the quantity of gas flowing through the tubes.

The operation of my automatic igniter is as follows: The gas escaping from the pilot tube 16 burns continuously in front of the opening 15, as this tube is not controlled by the valve in the pipe 11. Upon opening of the valve in said pipe 11, the gas will flow to the burner 10 and at the same time a column of gas will rise in the vertical section 14 of the member 13 and escape in a fine jet through the opening D and toward the burner 10. This jet of gas will pass directly over the pilot light at the end of the tube 16 and will be ignited thereby and will in turn ignite the gas issuing from the openings 12 in the burner 10. Now should the flame of the burner 10 be extinguished by water boiling over from the vessel being heated, or by a draft or for any

other reason, the burner will be immediately re-ignited by the jet of flame issuing from the opening D. The pilot light is protected against water and drafts by the curved hood 5 or shield 14', so that so long as the gas is flowing to the burner 10; a jet of flame will issue from under the hood 14' and strike the burner 10.

Variations from the specific form shown 10 and described may be resorted to within the scope of the appended claims without departing from the spirit of my invention.

I claim:

1. The combination with a gas burner 15 having a feed-pipe for conducting gas from a controlling valve thereto; of an angular member comprising a substantially tubular section projecting into said pipe and an arched hood section at an angle to said tubular section, the latter having an opening above the level of said burner for directing a jet of gas beneath said hood section and against the burner, and a pilot located within said hood section for igniting said jet.

2. The combination with a gas burner 20 having a feed pipe for conducting gas from

a controlling valve thereto; of an angular deflector of two sections having one section thereof partially projecting into said pipe transversely thereof and provided with an opening substantially parallel to said pipe for directing a jet of gas externally thereof and toward said burner, the other section of said deflector forming a hood extending along said pipe in the direction of the 30 burner, and a pilot adjacent said opening.

3. The combination with a gas burner 35 having a feed pipe for conducting gas from a controlling valve thereto; of an angular deflector of two sections having one section 40 thereof projecting into said pipe and provided adjacent its outer extremity with an opening for directing a jet of gas externally of said pipe toward said burner, a pilot adjacent said jet, and a hood forming the other 45 section of said deflector and projecting from the outer extremity of the first named section in the direction of said burner and above said pilot.

In testimony whereof I have affixed my 50 signature,

DANTE RASO.
